SUPPORT APPARATUS FOR RESISTANCE HEATED SOURCE HOLDERS

Richard P. Radke, 10818 Reseda Blvd., Northridge, Calif.

Filed Jan. 6, 1964, Ser. No. 335,913

1 Claim. (Cl. 339—32)

This invention relates to vacuum evaporation apparatus and more particularly to a versatile support apparatus for resistance heated source holders.

The art of vacuum evaporation requires a means of providing extremely high temperatures to a source of material to be evaporated. Therefore, a resistance type source holder is employed for many applications. The source holder varies in configuration with the particular operation to be performed. For example, most manufacturers of source holders offer more than 100 different types of source holders. The source holder in turn must be supported and means must be provided to connect the source holder in series with an electrical power supply.

Prior art support or clamping devices for the source holders have been custom made to accommodate only one or a very limited number of source holders. The prior art supports for source holders generally have been constructed by bending heavy copper straps in the appropriate configuration and then bolting them directly to the electrical leads passing through the vacuum chamber. The ends of the heavy copper straps that are to support the source holder are then drilled and tapped to accommodate individual appropriate clamps and the source holder is supported by the clamps.

The support for source holders, described above, is usable only for the size source holder for which it is designed and it is generally restricted to the vacuum system in which it is mounted.

The present invention overcomes the disadvantages and limitations of the prior art supports for source holders by utilizing a stationary clamping block fixed to one end of a base block and at least one movable clamping block capable of being positioned opposite the stationary clamping block at various distances from the stationary clamping block. Both the stationary and the movable clamping blocks have means for clamping one end of the source holder in a variety of positions on the top and side of the clamping blocks.

The objects and advantages of the present invention will be more fully explained in the following description, with reference to the accompanying drawings, in which:

FIGURE 1 is a perspective view of the present invention;

FIGURE 2 is a perspective view of the present invention with two source holders in position; and

FIGURE 3 is a perspective view of the present invention with one of the movable clamping blocks moved toward the stationary block to accommodate an upright source holder.

Referring now to FIGURE 1, there is shown a base 10. The base 10 preferably is metal. A stationary clamping block 11 is fixed to one end of the base 10. The clamping block 11 is constructed of an electrically conductive material and has V grooves 12 in the top and side thereof. The grooves 12 are cut to accommodate the wire type source holders (shown in FIGURE 2).

Clamps 13, 14, 15 and 16 are removably positioned on the top and sides of clamping block 11. The method of positioning the clamps is a matter of choice, however, metal screws inserted in tapped holes in the clamping block 11 have proven to be very satisfactory. It should be noted that clamps 13 and 16 may be lowered by utilizing the two lowest tapped holes in the stationary block 11.

2

Movable clamping blocks 17 and 18 are separated from the base 10 by the supporting spacers 19. The spacers 19 are electrical insulating supports commonly used in the art.

5 The base 10 has holes 20 to accommodate screws (not shown) which pass through the holes 20 into tapped holes (not shown) in the bottom of the spacers 19. Therefore, the spacers 19 and consequently the clamping blocks 17 and 18 can be moved to change the distance between the movable clamping blocks 17 and 18 and the stationary block 11.

The clamping blocks 17 and 18 also have V grooves on the top and sides thereof to accommodate the wire type holders. Clamping blocks 17 and 18 have clamps 20, 21, 15 22 and 23, which are similar to clamps 13, 14, 15 and 16. The clamps on the movable clamping blocks 17 and 18 can be held in position in the same manner that the clamps on the stationary clamping block 11 are held in position.

A shield 24 is positioned between the two movable 20 clamping blocks and extends from one end of the base 10 to the slot provided in the stationary clamping block 11. Preferably a slot is provided in the base plate to accommodate the shield 24.

Instead of the holes 20, the base can have three slots 25 in each side to allow the positioning of the movable clamping blocks 17 and 18. Also the number of spacers 19 is optional.

A tapped hole 25 is provided in the stationary clamping block 11 such that an electrical connection can be made 30 to the clamping block 11. Similar tapped holes (not shown) can be provided in the movable clamping blocks 17 and 18 to accommodate other electrical connections. The electrical connection can be made also directly to one or more of the clamps on each of the clamping blocks.

35 Referring now to FIGURE 2, a typical "dimple" type source holder 26 has one clamped to the stationary clamping block 11 and the other end clamped to the movable clamping block 17. Also a typical wire type source holder 27 has one end clamped to the stationary clamping block 11 and the other end clamped to the movable clamping block 18.

It can now be seen that one material can be evaporated from the source holder 26 and another material evaporated from the source holder 27. The shield 24 shields 45 the material in one source holder from the vapors given off by the material in the other source holder.

When the movable clamping blocks 17 and 18 are electrically connected to individual power supplies and the stationary clamping block 11 is electrically connected 50 to a common ground, the material in the source holders 26 and 27 can be evaporated at the same time or at different times.

When a wide source holder is employed, the shield 24 can be removed and both movable clamping blocks 17 and 18 used to support one end of the wide source holder. In such case only one electrical connection need be made to either one of the movable clamping blocks.

Referring now to FIGURE 3, a single source holder 28 is held by the side clamps 13 and 20. Note that clamp 60 13 is in the lower position to receive and make electrical connection with the bottom lead 29 from the source holder 28 and clamping block 17 has been moved closer to the stationary clamping block 11 in order to support and make electrical connection with the top lead 30 from 65 the source holder 28. Also a boat type source holder 31 is held by the side clamps 16 and 31.

It can be readily seen that the present invention can support many different types of source holders yet the present invention is very inexpensive to manufacture. 70 Also the present invention can be transferred from one vacuum system to another merely by disconnecting the

electrical leads (not shown) to the clamping blocks 11, 17 and 18.

The materials used to construct the present invention can be any of the normal materials used inside of vacuum chambers. These materials are well known to those skilled in the art. 5

Although the present invention has been described with reference to the preferred embodiment, it is understood that changes can be made without departing from the scope of the invention and the scope of the invention is set forth in the following claim. 10

What I claim is:

A device for holding a resistance heated source holder, comprising:
 an electrically conductive base; 15
 an electrically conductive stationary clamping block in electrical contact with and fixed to one end of said base;
 means for connecting said stationary clamping block to a source of electrical power; 20
 two movable electrically conductive clamping blocks attached to and insulated from said base, said movable clamping blocks being positioned such that a plurality of resistance heated source holders can be positioned between said stationary clamping block and said movable clamping blocks; 25
 means for individually connecting said movable clamping blocks to a source of electrical power;
 said base having openings selectively therein, thereby permitting said movable clamping blocks to be 30 fastened to said base in a variety of locations;
 a plurality of top and side clamps individually associated with said stationary and each of said two mov-

able clamping blocks such that any combination of top and side clamps on said stationary clamping block and one of said movable clamping blocks can be used to support a variety of various configurations of source holders; and
 a shield positioned on said base and between said two movable clamping blocks and extending the full length of said base up to said stationary clamping block, the vertical height of said shield being at least as high as said clamping blocks.
